(57) **CLAIM**

The ornamental design for card with a blue ornamental rectangle, as shown and described.

DESCRIPTION

FIG. 1 is a perspective view of a card with a blue ornamental rectangle showing my new design;

FIG. 2 is a front view of the card with a blue ornamental rectangle of FIG. 1;

FIG. 3 is a rear view of the card with a blue ornamental rectangle of FIG. 1;

FIG. 4 is a right side elevational view thereof;

FIG. 5 is a left side elevational view thereof;

FIG. 6 is a front elevational view thereof; and,

FIG. 7 is a rear elevational view thereof.

The centrally positioned rectangle in FIGS 1 and 2 has been shaded to indicate the color blue.

The numerals and indicia depicted by means of broken lines in the drawing are shown for illustrative purposes only and form no part of the claimed design.
